DESIGN FOR A COMBINED CIGARETTE SNUFFER AND TRAY

Paul Schildknecht, Los Angeles, Calif.

Application August 23, 1938, Serial No. 79,515

Term of patent 3½ years

To all whom it may concern:

Be it known that I, Paul Schildknecht, a citizen of the United States, residing at Los Angeles, in the county of Los Angeles and State of California, have invented a new, original, and ornamental Design for a Combined Cigarette Snuffer and Tray, of which the following is a specification, reference being had to the accompanying drawing, forming part thereof.

I claim:

The ornamental design for a combined cigarette snuffer and tray, as shown.

PAUL SCHILDKNECHT.
